DOLL CONSTRUCTION

Matteo De Cesare, Newark, N. J., and David Cohn, Brooklyn, N. Y., assignors to Eyedoll Corporation, Jersey City, N. J., a corporation of New Jersey

Application March 20, 1935, Serial No. 11,921

13 Claims. (Cl. 46—169)

This invention relates to doll construction.

An object of this invention is to provide in doll construction having rotating eyes, improved means for resiliently pressing the eyes into the 5 sockets of the doll's head, the construction being such that the doll's head may be readily assembled and loosening of the mechanism within the doll's head practically prevented.

A further object of this invention is to provide 10 a compact and rugged doll construction of the character described, which shall comprise few and simple parts, be relatively inexpensive to manufacture, smooth and positive in operation and withal practical and efficient to a high 15 degree.

Other objects of this invention will in part be obvious and in part hereinafter pointed out.

The invention accordingly consists in the features of construction, combinations of elements, 20 and arrangement of parts which will be exemplified in the construction hereinafter described, and of which the scope of application will be indicated in the following claims.

In the accompanying drawing, in which is 25 shown one of the various possible illustrative embodiments of this invention,

Fig. 1 is a cross-sectional, elevational view of a doll's head embodying the invention;

Fig. 2 is a cross-sectional view of the doll's 30 head in horizontal position;

Fig. 3 is a cross-sectional view taken on line 3—3 of Fig. 1; and

Fig. 4 is a cross-sectional view taken on line 4—4 of Fig. 3.

Referring now in detail to the drawing, 10 designates a doll's head embodying the invention. The head 10 comprises a front molded section 11 and a rear molded section 12 having meeting edges 13. The front of the doll's head 40 is provided with eye sockets 14 and with a central recess 15 above the eye sockets. Said head portion 11 is also formed on the inner surface thereof adjacent the chin with an abutment or thickened portion 15a, and adjacent the edge 45 13 thereof with a pair of notches 16 receiving the ends of a transverse, horizontal rod.

Fixed within the head is a rail member 18 the front end 19 whereof is received in the recess 15 and having a top wall 22 and downwardly 50 extending side flanges 23 formed with openings 20 adjacent the rear end thereof, for the rod 17. The rod 17 may be upset on opposite sides of the rail member 18 to prevent sidewise movement of said rail member. Mounted on the rail 18 55 is a member 25 made of an elongated strip of bent metal having a straight portion 26 formed with a slot or opening 27 to receive said rail. The distance between the upper edge 28 of the slot and the lower edge 29 thereof is made

greater than the height of the rail member for the purpose hereinafter appearing.

Extending downwardly from the upper portion 26 is a downwardly and rearwardly inclined portion 30 having a slot 31 at the lower end thereof for the upper portion of the rail 18. Extending downwardly from said portion 26 is a forwardly inclined portion 32. Riveted to said portion 32 is a strip spring 33 having an upwardly extending portion 34 formed with a slot 35 receiving the rail therethrough. Extending downwardly from the portion 34 is a rearwardly inclined portion 36 contacting the top wall 22 of the rail 18. The spring 36 tends to rock the member 25 about the edge 28 in a counter-clockwise direction to bring the edge 29 into engagement with the lower edges of the side flanges 23.

Disposed within the doll's head is an improved eye unit 40 comprising a square axle or bridge 41 to the central portion of which there is attached a U-shaped strap 42 rotatable therewith. Fixed to the central portion 43 of the strap 42 is a metal strip 44 carrying a weight 45. Mounted on the outer ends of the axle 41 are a pair of substantially hemi-spherical, hollow doll's eyes 50 having diametrically disposed square openings 51 receiving said outer ends of the axle therethrough.

The doll's eyes 50 are disposed in the sockets 14 of the doll's head. Rotatably mounted on the portion of the eye axle between the arms of the strap 42 is a spring 52 made of a strip of spring metal and having a circular portion 53 rotatably receiving said portion of the axle. The spring 52 extends downwardly and the free lower end 55 thereof is adapted to contact the abutment 15a of the doll's head. The bottom end of the portion 32 of said member 25 contacts the rear surface of the spring 52 between the portion 53 and the end 55 thereof for resiliently pressing the eyes 50 into the sockets 14.

The member 25 may be moved forwardly on the rail 18 by pressing the bottom end thereof forwardly to rotate the rocking member in a clockwise direction about the upper edge 28 of the opening 27, thus moving the lower edge 29 away from the bottom edges of the flanges 23. Rearward pressure on the bottom end of the member 25 will not move said member 25 rearwardly on the rail member because of the inter-engagement of the edges 28 and 29 with the rail member to rock the member 25 thereon. The member 25 may be moved rearwardly on the rail member by pressing against the upper end 55 thereof above the rail in a rearward direction to rock said member about the lower edge 29 of the opening 27.

It will now be understood that the rail member 18 may be assembled with the rod 17 and

then fitted into the front portion 11 of the head with the member 25 disposed adjacent the rod 17. The rear portion 12 of the head may then be assembled with the front portion 11 to fix the 5 rail member and rod within the head. The eye unit 40 may then be inserted through the neck opening of the doll's head and the member 25 then pushed forwardly by exerting pressure thereon below the rail in a forward direction until the 10 bottom end of the portion 32 contacts the spring 52.

It will thus be seen that there is provided a device in which the several objects of this invention are achieved, and which is well adapted 15 to meet the conditions of practical use.

As various possible embodiments might be made of the above invention, and as various changes might be made in the embodiment set forth, it is to be understood that all matter here- 20 in set forth or shown in the accompanying drawing, is to be interpreted as illustrative and not in a limiting sense.

Having thus described our invention, we claim as new and desire to secure by Letters Patent:—

25 1. In doll construction, a doll's head having eye sockets, an axle having eyes thereon received within said sockets, a weight fixed to said axle, a spring having a portion thereof freely encircling said axle and another portion thereof 30 freely contacting a portion of the doll's head, and means for pressing an intermediate portion of said spring for resiliently pressing the eyes into the sockets, said axle being unsupported.

2. In doll construction, a doll's head having 35 eye sockets, an eye unit comprising an axle having eyes mounted thereon, a weight fixed to said axle and a strip spring having a portion rotatably receiving said axle, and an elongated portion extending from said first portion, said elongated 40 portion being adapted to freely contact the doll's head and means cooperating with said strip spring for resiliently maintaining the eyes in said sockets, said axle being unsupported.

3. In doll construction, a doll's head formed 45 with eye sockets, an eye unit comprising an axle with doll's eyes on the ends thereof received within said sockets, a weight fixed to said axle for rotating the same, a strip spring mounted on said axle and having a portion freely contacting the 50 doll's head, and means within the doll's head pressing against said spring for yieldingly maintaining said eyes within said sockets, said axle being unsupported.

4. In doll construction, a doll's head formed 55 with eye sockets, an eye unit comprising an axle with doll's eyes on the ends thereof received within said sockets, a weight fixed to said axle for rotating the same, a strip spring rotatably mounted on said axle and having a portion free- 60 ly contacting the doll's head, and means within the dolls head pressing against said spring for yieldingly maintaining said eyes within said sockets, said axle being unsupported.

5. In doll construction, in combination, a doll's 65 head having eye sockets, a rail member fixed within said head and extending from front to rear thereof, a member on said rail, a doll's eye unit comprising an axle having doll's eyes thereon received within said sockets, a spring on said 70 axle engaging said head, and means on said member engaging said spring at a point spaced from said axle for yieldingly pressing said eyes within said sockets.

6. In doll construction, in combination, a doll's 75 head having eye sockets, and an abutment on the

inner surface thereof adjacent the chin, a rail member fixed within said head and extending from front to rear, an eye unit comprising an axle having doll's eyes thereon received within said sockets, a weight attached to said axle, a 5 spring mounted on said axle and having the lower end thereof contacting said abutment, and means on said rail member engaging said spring for resiliently pressing the eyes into said sockets.

7. In doll construction, in combination, a doll's 10 head having eye sockets, and an abutment on the inner surface thereof adjacent the chin, a rail member fixed within said head and extending from front to rear, an eye unit comprising an axle having doll's eyes thereon received within 15 said sockets, a weight attached to said axle, a spring rotatably mounted on said axle and having the lower end thereof contacting said abutment, and means on said rail member engaging said spring for resiliently pressing the eyes into 20 said sockets.

8. For use in combination with a support therefor, an eye unit for a doll's head comprising an axle having a pair of eyes mounted thereon, a weight fixed to said axle and a spring having one end thereof rotatably mounted on said axle, and having the other end thereof free, said free end being adapted to contact an abutment in said doll's head, said axle being unsupported. 25

9. For use in combination with a support 30 therefor, an eye unit for a doll's head comprising an axle having dolls eyes mounted thereon, a weight fixed to said axle and a spring rotatably mounted on said axle, said axle being unsupported. 35

10. For use in combination with a support 40 therefor, an eye unit for a doll's head comprising an axle having doll's eyes mounted thereon, a weight fixed to said axle and a spring rotatably mounted on said axle, said spring being made of an elongated strip of spring metal, said axle being unsupported. 45

11. In doll construction, a doll's head having 50 eye sockets, an axle having eyes thereon received within said sockets, a weight fixed to said axle for rotating the same, a spring carrying said axle, said spring having a portion thereof freely contacting the doll's head, and resilient means for pressing said spring for yieldingly maintaining said eyes within said sockets, said axle being unsupported. 55

12. In doll construction, in combination, a doll's head having eye sockets, a rail member fixed within said head and extending from front to rear thereof, a member slidably adjustable on said rail, a doll's eye unit comprising a square axle having doll's eyes thereon received within said sockets, a spring on said axle engaging said head, and means on said slidably movable member engaging said spring at a point spaced from said axle for yieldingly pressing said eyes within said sockets. 60

13. In doll construction, a doll's head provided with eye sockets, an eye unit comprising an axle having mounted thereon eyes adapted to be received in said sockets, and means for yieldingly pressing said eyes within said sockets whereby said eyes are free to adjust themselves to variations in alignment of the eye sockets, said last named means comprising a spring carrying said axle and a second spring pressing against said axle-carrying spring. 65 70
